CLAIM

The ornamental design for a vehicle rear fascia, as shown and described.

DESCRIPTION

FIG. 1 is a perspective view of the vehicle rear fascia; FIG. 2 is a left side elevation view thereof; FIG. 3 is a top plan view thereof; and, FIG. 4 is a front view thereof.

The right side elevation view of the vehicle rear fascia is omitted because the right side elevation view is identical to the left side elevation view. And the broken lines shown in the drawings depict portions of the vehicle rear fascia that form no part of the claimed design. Further, the rear of the vehicle rear fascia forms no part of the claimed design.
